UNITED STATES PATENT OFFICE.

LÉON EMILE RÉMONDY, OF RUEIL, FRANCE.

FUSE FOR PROJECTILES.

Application filed April 6, 1925. Serial No. 21,136.

To all whom it may concern:

Be it known that I, LÉON EMILE RÉMONDY, a citizen of the Republic of France, resident of Rueil, France, have invented new and useful Improvements in Fuses for Projectiles, which are fully set forth in the following specification.

This invention relates to fuses and more particularly to nose fuses of the percussion type.

In my Patent No. 1,459,075, dated June 19, 1923, there is disclosed an extremely sensitive percussion fuse and one which may be handled with entire safety. The characteristics of this fuse result from the use of an extremely light carriage containing the whole of the firing mechanism, which latter comprises a primer and striker with a resilient member interposed between the two. Means such as a shear pin and if desired a suitable plastic body, normally prevent the carriage from being driven into the fuse body before an obstacle is struck.

The operation of such a fuse, when an obstacle is struck, is sure, even if the resistance offered by the obstacle is very slight, as in the case of the covering fabric of aeroplanes for example. This positive action is due to the fact that the fuse body (rigidly attached to the projectile) and the carriage are caused to become independent of each other as a result of the impact, the retaining means (pin, air pressure or the like), which previously prevented the carriage from being driven in, being then rendered inoperative.

An obstacle which offers very little resistance, and is not capable of stopping or retarding greatly the projectile, is sufficient to stop the extra light carriage or to considerably retard it, the projectile continuing its forward movement. The back part of the firing mechanism, which is free in the carriage, also continues to move and meets the front part before the carriage can reach the bottom of its lodgment, and be again carried forward by the projectile. The kinetic energy ($1/2mV^2$) of this free part comes into action, and the force of the impact between the latter part and the front part, which is retarded or stopped independently of the projectile, is proportional to the difference between the residual speed of the movable part of the mechanism and the speed of the carriage.

If V is the velocity of the projectile, and consequently of the movable part, at the moment a light obstacle is struck, and v the retarded velocity of the carriage (which velocity, due to light weight of the carriage, will most frequently approach zero), the kinetic energy of the back part of the mechanism (of the detonator, for example) will be $1/2m(V-v)^2$. The factor $(V-v)^2$, when the projectile strikes the obstacle, has obviously a very high value, due to the very high value of V and to the very small value of v .

In order to ensure that the mechanism will act it is therefore allowable to give to m , that is to say to the mass of the movable part of the mechanism, a very small value, the opposite of which is the case in the greater part of the usual percussion fuses, in which it has been sought, on the contrary, to increase the mass of the movable part in order to increase the sensitiveness of the fuse, which immediately led to the use of complicated safety devices, which were indispensable in order to prevent an untimely action of the fuse from occurring, as a result of a fall from a small height, during handling and transport.

The fuse disclosed in the patent referred to above is very sensitive, due to the extreme lightness of the carriage and of the movable part contained in the latter; this sensitiveness is also accompanied by the complete safety of the fuse, due to the fact that the fuse can only act when the factor V^2 in the kinetic energy $1/2mV^2$ of the movable part is sufficiently great; this factor V^2 only reaching the desired value for the impact between the parts of the mechanism to produce ignition, if the projectile itself possesses, at the moment this impact takes place, a velocity comparable with the velocity with which it leaves the muzzle of the gun.

It has been shown above that the action of the fuse when a very light obstacle is struck is due to the kinetic energy liberated $1/2m(V-v)^2$ by the movable part of the mechanism which moves so as to strike the fixed part which is stopped or retarded. Now, it is quite obvious that the factor $(V-v)^2$ will be as much greater as v will be less against a given obstacle, and v itself will be as much smaller as the carriage is lighter and, consequently, easier to retard.

Accordingly the present invention is di-

rected to a fuse comprising a movable carriage, containing the firing elements, which carriage and elements are made as light as possible. By lightening the carriage either 5 the sensitiveness of the fuse may be increased, or, for the same degree of sensitiveness of action, less sensitive detonators (percussion caps) or shorter and less pointed strikers may be employed. That is 10 to say, by lightening the carriage, either the sensitiveness or the safety of the fuse may be increased, always, of course, without introducing additional heavy and cumbersome devices.

15 It will immediately be seen that, following this last line of reasoning it is possible, with a less sensitive detonator or percussion cap and a less pointed striker, to dispense with the separating member provided between these parts, since an untimely impact between them could not cause the detonator to be ignited, the kinetic energy of the latter being insufficient, for low velocities of the projectile, to produce a sufficient force of impact.

30 The invention will be readily understood by reference to the accompanying drawings wherein like reference characters refer to like parts throughout the several views, and wherein,

Fig. 1 is a side elevation partly in section, illustrating one embodiment of the present invention;

35 Fig. 2 is a sectional view illustrating one form of the invention which includes a resilient member between the primary and striker:

40 Fig. 3 is a sectional view similar to Fig. 2 illustrating another embodiment of the present invention;

Fig. 4 is a section on the line 4, 4 of Fig. 3;

45 Fig. 5 is a view similar to Fig. 3 illustrating the position of the elements shown in Figs. 3 and 4 at the moment of impact; Figs. 6, 7 and 8 refer to another embodiment of the present invention; Fig. 6 being a sectional side view showing the normal position of the parts, Fig. 7 a section taken on the line 7, 7 of Fig. 6, and Fig. 8 a sectional view illustrating the relative position of the parts at the instant of impact;

55 Figs. 9 and 10 are sectional side elevations illustrating two other embodiments of the present invention; and

60 Figs. 11 and 12 are a sectional side elevation and a top plan view respectively of still another embodiment of the present invention, Fig. 11 being taken on the line 11 of Fig. 12.

65 Referring to Figure 1, A is the fuse body. The extra light carriage, which encloses the whole of the mechanism, consists of two stampings, B and C, one of which, C, may be slightly domed to form an impact cap.

A striker c is formed centrally of the stamping C by forcing the metal of the latter inwardly. The other stamping B, in which the first part may be hooked or set, forms the body of the carriage and contains the loose back part of the firing mechanism, viz the detonator D. Any forward movement of the arrangement B—C may be prevented by a setting formed by turning down the edge a of the fuse body over the edges 75 of the stamping C.

The carriage may be prevented from being driven into the fuse body by the provision of a simple ring or washer E made of cork, felt, or of any other suitable plastic or compressible material, sitting on a lodgement provided for the purpose in the fuse holder, and held between the expanded head of the carriage and a shoulder a¹ formed 80 on the fuse body.

If a sufficiently short and blunt striker, together with a detonator possessing a sufficiently small degree of sensitiveness is used, it is possible, as shown in the figure, to dispense with any flexible or plastic separating member between the striker c and the detonator D.

95 If a projectile fitted with the fuse of the present invention be dropped from a small height, the velocity acquired by the projectile at the moment it strikes the obstacle (the ground, deck of a vessel, platform or the like) will in fact compress the plastic material E and, consequently force the carriage B—C rearwardly in the duct A¹, thus causing an impact to take place between the detonator D and the striker c, before the carriage has arrived at the end of its stroke: but the kinetic energy $1/2mV^2$ of the detonator (which may act while the carriage moves towards the interior of the fuse body) 105 will then be too small, on account of the very small values of m and V, for the impact between D and c to cause the detonator to be ignited.

110 The plastic mass E is on the other hand sufficient to prevent any recoil of the carriage in the fuse body, when the shot is fired, since the carriage C—B—D is extraordinarily light, for its weight may be of the order of one or two decigrams (0.2 grams).

115 These two conditions which are necessary, and sufficient for the fuse to operate, that is to say for the plastic retaining material E to be compressed and for a suitably violent impact to take place between the striker c and the detonator D, will be definitely fulfilled however small the resistance offered by the obstacle struck, provided that the velocity V of the projectile and of the detonator when this obstacle is struck, has a suitable value. If the obstacle stops or even simply retards the very light carriage, without materially effecting the velocity V of the projectile and of the detonator, the value 120

$V-v$ (where v is the residual velocity of the carriage) will remain very high, and the value of $1/2m(V-v)^2$ will be sufficiently high for the impact between c and D to produce the ignition of the detonator.

Naturally, a separating member such as a spring F , for example, as shown in the modification in Figure 2, may be disposed in the interior of the carriage without materially increasing its weight.

In this modification, the stamping C , at the base and the centre of which is formed the striker c , comprises a cylindrical part sleeved in the stamping B . The bottom of the detonator D , lodged in the interior of the stamping C , abuts against the bottom of the stamping B , and is held away from the point of the striker by a spring F the tension of which is such that it cannot be compressed, due to the effect of the kinetic energy of the detonator, unless the quantity $V-v$ has a suitable value. The edge a of the fuse body is turned down over the edge of the front enlarged part B^1 of the stamping B .

In the embodiment of the invention illustrated in Figs. 3 and 5, the stampings B and C are of similar shape to those shown in the example illustrated in Figure 1.

Here, the stamping B is provided with apertures b placed diametrically opposite each other, in which engage the wings g of a ring or washer G , the said wings being gripped between the back face of the plastic material E and the shoulder a^1 on the fuse body.

When, due to the influence of the impact of the projectile with an obstacle, even one which offers very little resistance, the carriage $B-C$ is stopped or retarded, the plastic material E is compressed, which enables the said carriage to be driven into the fuse body, the apertures b of the stamping B being displaced over the wings g of the ring or washer G . The detonator D , which continues to move forward with the velocity V of the projectile, meets the striker c with a kinetic energy $1/2m(V-v)^2$ where v is the residual velocity, approaching zero, of the carriage $B-C$.

Referring to Figs. 6 to 8 inclusive, the carriage containing the whole of the mechanism is constituted by a stamping B , inside which is lodged the detonator D , and by a disc C . The central part of this disc is cut as shown in Figure 7, so as to form one or more pointed parts c which, under the influence of an external pressure, may be made to project from the internal face of the disc. The member which normally prevents the carriage $B-C$ from being driven into the lodgment formed in the fuse body, may, as in the preceding examples, consist of a small sleeve E , made of cork or any other suitable material. A plug H , made

of cork or any other plastic material normally prevents the carriage from moving out of the fuse body.

When the plug H strikes an obstacle, even one which offers very little resistance, the material of which this plug is made is driven towards the interior. At the same time as it compresses the sleeve E , through the medium of the disc C , the plug H bends down the central part of the disc, so as to make the point c project from the internal face of the latter. Ignition takes place, as in the preceding examples as a result of the driving in of the carriage $B-C$, while the projectile and the detonator D continue their forward movement, which causes an impact between the detonator and the striker to take place.

It is seen that in this case it is unnecessary to provide any safety device or any separating member between the detonator D and the disc c , the striker being only formed as the result of an impact between the carriage and the obstacle, or more exactly, between the obstacle and the plug H of plastic material which surmounts the carriage.

The shape of the cuts made in the disc C , the number of these cuts, and the nature of the plug of plastic material may naturally be varied as desired.

It goes without saying that the striker, which is formed by a deformation of the external cover or base of the carriage, instead of being formed in a disc may be formed on a base which forms a part of any other stamping.

It is to be noted that the new means, consisting in the striker being formed when the fuse enters into operation, may also be employed with a fixed carriage, containing a movable detonator or a fixed detonator. In the latter case, the deformation of the disc in which the striker is cut would follow the formation of the striker and would effect the ignition.

Figure 9 shows, in longitudinal sectional elevation, a form of construction in which the two stampings B and C are combined in one single one.

In this case the back end of the stamping is formed by the edge of the cylindrical body which is turned down internally. The sleeve E , made of plastic material, is gripped between this end and the shoulder a^1 of the fuse body. The stamping as in the preceding example, is prevented from moving forward by a setting of the open end a of the fuse body.

The detonator D preferably rests on a ring or washer d made of plastic material.

Referring to the embodiment of the invention shown in Fig. 10, the two stampings B and C are combined in one; in the cylindrical body B are formed apertures b which enable it to slide over a ring or washer $G-g$

provided with wings, similar to the one shown in the form of construction illustrated in Figures 3 and 4.

The plastic material which forms the means for preventing any backward movement of the movable carriage B—C—D is constituted by a sleeve E, made of cork, felt or the like suitable material, lodged in the interior of the stamping B around the striker c and resting by means of its front face against the end C, while its back face presses against, the ring or washer G. The wings may be rendered stationary by means of a small cylindrical liner H, over the front face of which the front edge a of the fuse body is turned down. It will be seen in this case that the plastic material E, at the same time as it forms a means for retaining the carriage in its extreme forward position, forms a separating member preventing any untimely approach of the detonator and the striker towards each other until an obstacle is struck.

Referring to the embodiment of the invention illustrated in Figs. 11 and 12, the plastic material E which forms a means for retaining the carriage B—C is replaced by flexible tongues C¹ forming projections on the disc C and engaging in small mortices A² formed in the front face of the fuse body. These tongues C¹ are fixed in position by the lips a^2 of the mortices being bent over, after the carriage has been placed in position in the said mortices.

When an obstacle is struck, the carriage B—C is driven into the duct A¹, the tongues C¹ giving way under the force of the impact.

Having now particularly described and ascertained the nature of my said invention and in what manner the same is to be performed, I declare that what I claim is:

1. A fuse for projectiles comprising a fuse body having a duct formed therein, a hollow carriage movably mounted within the said duct, a cover for said carriage, a striker integral with the said cover, and a detonator within the said carriage.

2. A fuse for projectiles comprising a body portion having a duct therein, a hollow carriage formed by stamping mounted in said duct adjacent one end thereof, a detonator mounted for movement in the rear end of the carriage, and a striker formed in the forward wall of the carriage and integral with said wall.

3. A fuse for projectiles comprising a fuse body, a hollow carriage movably mounted therein, a detonator within said carriage and a striker formed by one wall of the carriage.

4. A fuse for projectiles comprising a fuse body, a hollow carriage movably mounted therein, a cover for said carriage, a striker formed integrally with and centrally of said cover, and a detonator within said carriage.

5. A fuse for projectiles comprising a fuse body, a hollow carriage movably mounted therein, a cover for said carriage, a striker comprising a projection formed in the cover and a detonator within said carriage.

6. A fuse for projectiles, comprising a fuse body, a movable carriage mounted therein, a cover for said carriage, a striker formed in the cover comprising a portion displaced centrally thereof, and a detonator within said carriage.

7. A fuse for projectiles comprising a fuse body having a duct leading to the interior thereof, a carriage movably mounted in said duct, a striker projecting inwardly from one end of the said carriage, a detonator within the carriage, and means formed on the fuse body adjacent the mouth of the duct to prevent outward movement of the carriage.

8. A fuse for projectiles comprising a fuse body having a duct formed therein, a carriage mounted in the said duct, said carriage comprising a pair of stampings, one of which forms the base and the other of which forms the cover of the carriage, a striker projecting inwardly of the carriage from the cover, and a detonator within the base of the carriage.

9. A fuse for projectiles comprising a fuse body having a duct formed therein, a carriage mounted in the said duct, said carriage comprising a cylindrical base portion open at one end, a flange formed on the base adjacent its open end, a cover for said base, a striker comprising a projection displaced centrally of the cover, and a detonator within the said base of the carriage.

10. A fuse for projectiles comprising a fuse body having a duct formed therein, a carriage having an enlarged head mounted in the said duct, a striker projecting inwardly of the carriage from the said head, and a detonator within the carriage in unrestricted communication with the striker.

11. A fuse for projectiles comprising a fuse body having a duct formed therein, a carriage mounted in the said duct, said carriage comprising a cylindrical body portion and an enlarged cover therefor, a striker formed centrally of and projecting inwardly from the said cover, and a detonator loosely supported within the body portion of the said carriage.

12. A fuse for projectiles comprising a fuse body having a duct leading to the interior thereof, an annular shoulder formed adjacent the outer end of said duct, a carriage movably mounted in the said duct, an enlarged head formed on the said carriage and adapted to project over said annular shoulder, a striker formed centrally of and projecting inwardly from the said enlarged head, resilient means interposed between said enlarged head and said annular shoulder to resist inward movement of the said

carriage, and a detonator loosely supported within said carriage.

13. A fuse for projectiles comprising a fuse body having a duct leading to the interior thereof, an annular shoulder formed adjacent the outer end of the said duct, a carriage movably mounted in the duct, said carriage comprising a cylindrical body portion and an enlarged dome-shaped head, means interposed between the said enlarged head and the annular shoulder to yieldingly re-

sist inward movement of the carriage, an annular flange formed adjacent the mouth of the duct to limit outward movement of the carriage, a striker formed centrally of and projecting inward from the enlarged head, and a detonator within the cylindrical body portion of the carriage in unrestricted communication with the said striker. 15

In testimony whereof I have signed this 20
specification.

LÉON EMILE RÉMONDY.
